SOUND REPRODUCTION

Hillel I. Reiskind, Indianapolis, Ind., assignor to
Radio Corporation of America, a corporation of
Delaware

Application April 30, 1941, Serial No. 391,161

9 Claims. (Cl. 179—100.3)

This invention pertains to the reproduction of sound, and, more particularly, to the photoelectric reproduction of sound from film type sound records. In a sound reproduction system to which this invention is applicable, a plurality of loudspeakers or sets of loudspeakers are used, and the reproduction of sound through the several speakers is controlled as to both volume and placement in a predetermined manner by a special control track recorded on the film and reproduced concurrently with the sound track.

This application is in general an improvement on the apparatus described and claimed in M. C. Batsel's application Serial No. 302,197, filed October 31, 1939 (RCV D-6981), wherein a speaker centrally located in relation to a picture screen or other object space is used generally for the reproduction of voice, and additional speakers are connected into the circuit on each side of the central speaker or at other locations for reproduction of music or sound effects. The control record is preferably of the type described and claimed in C. M. Burrill's application Serial No. 181,634, filed December 24, 1937, wherein a control record is placed in the sprocket hole area of the sound record or motion picture film, and the sprocket hole frequency is used as a carrier frequency which is modulated in amplitude in accordance with the control effect desired. The sprocket hole frequency may be modulated as to frequency, if desired, in accordance with C. M. Burrill's application Serial No. 181,635, filed December 24, 1937. The invention is not limited, however, to the use of these specific types of control tracks, as the control track might be located in the margin of the film beyond the sprocket hole area, as described for example in British Patent 309,208 to Wilson. Alternatively, a subaudible or supraaudible control frequency might be superposed on the sound record as described and claimed in Ringel Patent 2,029,389, issued February 4, 1936.

The present invention involves a novel method of and apparatus for controlling the speakers and amplifiers by means of the control track or control frequency, and involves the placing into operation or removing from operation of additional speakers and amplifiers either with or without change of volume at the time the additional elements go into or out of operation and the subsequent control of the volume of reproduction from either all or a selected portion of the speakers.

One object of the invention is to provide an

improved apparatus for controlling the placement of sound reproduction.

Another object of the invention is to provide an improved apparatus for controlling the volume of sound reproduction.

Another object of the invention is to provide an improved film sound reproducer.

Another object of the invention is to provide means for selectively or collectively controlling a plurality of sound reproducers.

Another object of the invention is to provide improved variable gain amplifiers for controlling the volume of sound reproduction.

Other and incidental objects of the invention will be apparent to those skilled in the art and from a reading of the following specification and an inspection of the accompanying drawings in which:

Figure 1 is a block diagram of the preferred form of the invention.

Figure 2 shows one desired set of characteristic curves.

Figure 3 is a schematic diagram of the control amplifier indicated in Fig. 1.

Figure 4 is a schematic diagram of the first variable gain amplifier shown in Fig. 1.

Figure 5 is a schematic diagram of the second variable gain amplifier shown in Fig. 1.

Figure 6 shows the desirable characteristic for the apparatus in order to provide control of gain on the center speaker without the side speakers turned on.

Figure 7 illustrates the gain characteristics of the system shown in Fig. 8.

Figure 8 is a block diagram of a modified form of the invention using three variable gain amplifiers, and

Figure 9 is a schematic diagram of an arrangement for securing the same result as in Fig. 8 with only two variable gain amplifiers.

Referring first to the form of the invention shown in Fig. 1, the sound record 12 on the film is reproduced optically by one of the usual forms of reproducing system which is illustrated schematically as merely consisting of a scanning light 10 and a photocell 14. This scanning system is, of course, constructed in accordance with usual commercial practice and may include an optical system, a slit and other such elements as might be necessary or advisable to insure proper reproduction of the sound, there being many varieties of such system shown in the patented art. The control track at 13 is likewise reproduced by means of an appropriate light such as indicated at 11 and a photocell 15. The

output from the photocell 14 is passed through a voltage amplifier 16 which may be made in accordance with usual commercial practice and the output from the voltage amplifier is fed to the first variable gain amplifier 18 schematically illustrated in Fig. 4. The output from the variable gain amplifier 18 is fed to the power amplifier 20 and from there to the speakers 21 which are preferably located behind the middle portion of the motion picture screen or other center of interest.

The output from the photocell 15 is supplied to the control amplifier 17, a schematic diagram of which is shown in Fig. 3 and this control amplifier supplies three different control voltages two of which are applied to the variable gain amplifier 18 and the third of which is applied to a second variable gain amplifier 19. The variable gain amplifier 19 takes its input from a circuit between the variable gain amplifier 18 and the power amplifier 20 and the output from the variable gain amplifier 19 is fed through the power amplifier 22 to the speakers 24 which are located, respectively, at the sides of the screen speakers 21 and are preferably symmetrically located in respect thereto so as to give the effect of the reproduction of sound from an extended area when the side speakers are turned on.

In the control amplifier 17 the control signal from the track 13 is amplified, rectified, and filtered thereby providing a D. C. potential which is applied to the variable gain amplifiers referred to.

The solid lines in Fig. 2 represent one desired set of gain characteristics of the variable gain amplifiers plotted against the control track output. The point A of the control track output represents the minimum modulation from the control track, which is bucked out in the control amplifier so it has no effect on the system. This minimum modulation unavoidably occurs on any photographic type of control track or even on a mechanically reproduced control track due to the physical characteristics of the record material. For example, in the sprocket hole type of control track the film between the sprocket holes is not completely transparent and there is therefore a definite difference in transmission between the sprocket hole areas themselves and the intervening spaces even when there is no control track present and in addition to this the edges of the sprocket holes are not optically smooth surfaces and therefore have appreciable opacity.

As the space between the sprocket holes is progressively darkened by increasing either the width or density of the darkened area, the output of the control track amplifier rises until it reaches a maximum value. As the control track output increases from its minimum value A, the gain of the second variable gain amplifier 19 may be increased as indicated in the portion 30 of the lower curve of Fig. 2, thereby gradually bringing the side speakers into operation. During this period, the first variable gain amplifier 18 remains at a constant gain, as indicated by the line 32. At the point B, the side speakers are turned completely on as indicated in the portion 31 of the lower curve of Fig. 2, and thereafter the gain of the first variable gain amplifier 18 may be increased as indicated by the line 33 of the upper curve until maximum output from all the speakers is attained.

This arrangement has what, in some instances, may be a disadvantage in that the addition of 75

the side speakers 24 with their power amplifier 22 will increase the overall sound level by approximately 3 db. If these speakers are of the same power as the screen speakers, this effect may be avoided by decreasing the gain of the first variable gain amplifier 18, as indicated in the dotted line 34, as the side speakers are gradually brought into operation. The overall output then remains constant, as the side speakers are brought into operation and, after they are completely operating, the gain on the first amplifier 18 may be increased, as indicated in the dotted line 35, until the full output of the apparatus is attained.

The control amplifier for accomplishing this result is shown in detail in Fig. 3. The control track output from the photocell 15 is fed to the vacuum tube 36. This tube is of the pentode type and is operated as a logarithmic amplifier. As will be apparent from an inspection of the diagram, the positive terminal plate supply voltage is grounded and all voltages in the circuit are negative with respect to ground in order to secure negative bias on the grids of the variable gain amplifiers. The tube 36 is provided with the usual suppressor grid and screen grid which are connected in the customary manner, but the control grid nearest the cathode is rendered positive in relation to the cathode. It will be apparent from the circuit diagram that the photocell 15 is connected to a source of potential some 90 volts more positive than the cathode, and any current passing through the photocell 15 will, therefore, appear in the tube 36 in the form of grid current. Under this condition, the tube acts as a logarithmic amplifier, and the level of the A. C. signal produced is rendered independent of the brightness of the exciter lamp, being determined substantially entirely by the ratio between the maximum and minimum brightness, rather than the difference between maximum and minimum brightness as in the case of a linear amplifier. The plate of the tube 36 is supplied with potential through the usual feed resistor and the A. C. output thereof is applied through a capacitor to the potentiometer 42 which is used to select the amplitude of the control current applied to the grid of the tube 37. The tube 37 is, as shown, a pentode connected in the usual manner and serves to amplify the output of the tube 36. The output of the tube 37 is applied through the capacitors 43 and 44 to the rectifiers 38 and 40. Each of these rectifiers is a full wave rectifier connected as shown in a conventional doubler circuit, and differs from the usual practice only on the provision of the potentiometers 45 and 46 which provide a bucking bias on each of these rectifiers to eliminate the minimum output from the control track described above. The output from the rectifier 38 is supplied through the circuit shown to the amplifier 39. The potentiometer 47 at the output circuit of the rectifier 38 determines the average amplitude of the control potential applied to the tube 39, while the resistor 49, which may have a value as high as several megohms, and the capacitor 51, which may have a value of the order of 10 microfarad, serve as a filter. It will be apparent that, if the sprocket hole frequency of 96 cycles is used as described in the Burrill applications above referred to, this frequency will be doubled by the rectifier, giving a frequency of 192 cycles, which may be adequately filtered by the arrangement which is described, since the grid of the tube 39 is negative with respect to

the cathode and, therefore, no grid current is drawn. The plate current of the tube 39 is applied across the potentiometer 59 from which the control voltage of the circuit marked A in Figs. 1 and 4 is taken. If desired, this output circuit may be provided with further filtering means consisting of the resistor 53 of one megohm value and an appropriate condenser 56, which, like the condenser 51, may have a value of $\frac{1}{10}$ microfarad.

The first variable gain amplifier is shown in Fig. 4. In this amplifier the audio input is fed through the transformer 60 to the tube 61. The tube 61 is a standard type of exponential tube such, for example, as the type 6K7 the gain of which varies with the grid bias. The plate supply of this tube is fed through the inductance 61 while the audio frequency output is taken out through the transformer 65 connected in series with the capacitor 65' which acts as a blocking condenser. This arrangement prevents the flow of any direct current through the primary of the transformer 65 and thereby prevents saturation of the core.

In addition to the gain control, a loading tube 63 is provided. This tube is provided with a bias resistor 64 and which provides a normal grid bias. The tube 63 serves as a variable load in the plate circuit of the tube 61. The control voltage A applied to the variable gain amplifier, Fig. 4, is taken across the resistor 59 or capacitor 56 of Fig. 3, as described before, while the control voltage C is the voltage which appears across the capacitor 51 in Fig. 3. With a control voltage B sufficient to cut off the second variable gain amplifier indicated at 19 in Figure 1 the control voltage C is so adjusted as to put the proper load on the plate circuit of the tube 61. When the control track operates to drive the control voltage B to zero thereby turning on the power amplifier 22 and the loudspeakers, the control voltage C is also driven to zero thereby putting an additional load on the plate circuit of the tube 61 which load is determined by the plate-to-cathode resistance of the tube 63 and the value of the resistor 64. This reduction of the control voltage C reduces the gain of the first variable gain amplifier 18 of Fig. 1 and if the constants of the circuit are properly adjusted the operation of the device will follow the curve 34, 35 of Fig. 2 giving no observable change in level in the auditorium when the additional speakers are turned on. The control voltage A is varied in the manner before described and increases the gain of the tube 61 after the side speakers are switched on up to the point of maximum output as indicated in Fig. 2.

The connections to the second variable gain amplifier 19 which is used to turn on the side speakers are shown in Fig. 5. In this amplifier, the audio input from the first variable gain amplifier is supplied through the transformer 70 to the tube 71, which, like the tube 61 of the amplifier of Fig. 4, may be a type 6K7. The audio output from the tube 71 is fed through the transformer 74 to the power amplifier 22 of the side speakers, plate voltage being supplied to the tube 71 through the resistor 73. An appropriate voltage divider 72 provides the normal grid bias and screen potential for the tube. This amplifier is, as shown in the drawings, supplied with the control voltage developed across the capacitor 58 in the lower portion of the amplifier shown in Fig. 3, and this voltage is sufficient to bias the tube 71 completely to cut-off, being decreased as above described when it is desired to turn on the side speakers.

While the above described scheme of first turning on the side speakers and then volume-controlling the entire system is the one which is at present preferred, other modes of operation may be used. For example, it may be desired, under some circumstances, to control the volume of the system with only the center speaker operating and only turning on the side speakers after maximum gain has been reached on the first variable gain amplifier. Such an arrangement would have the advantage of providing a wider volume range for solo or dialogue parts, for example, which must be reproduced on a single speaker, while the multiple speaker system would be available for orchestra reproduction.

In order to secure this type of operation of the amplifiers, the controls of the amplifiers would have to be set in accordance with the curves shown in Fig. 6. In this instance, the potentiometer 45 would be set as before to buck out the control voltage up to the point marked "A," where the control signal starts to increase over the signal produced by the sprocket holes in clear film. Above this point, the gain of the first variable gain amplifier 19 increases as shown in the upper curve of Fig. 6. The potentiometer 47 is adjusted to drive the tube 39 to cut-off at a predetermined control voltage indicated at B on the curves of Fig. 6. The potentiometer 46 would be set to buck out the control voltage represented by the point B on the curves of Fig. 6 and above this voltage the signal from the side speakers would be gradually turned on. The potentiometer 48 is set to drive the tube 41 to cut-off at the control voltage C of the curves of Fig. 6, which is the maximum control voltage developed by the control track.

If it is desired to secure a combination of the foregoing effects, this may be done by so connecting the apparatus that the gain for the center speaker may be controlled, the side speakers may then be turned on, and the volume of the entire apparatus may thereafter be further increased.

One arrangement of apparatus for accomplishing this result is shown in Fig. 8, the operation of this apparatus being controlled in accordance with the curves of Fig. 7. The apparatus of Fig. 8 differs from that of Fig. 1 in the interposition of the additional variable gain amplifier 80 between the amplifier 18 and the power amplifier 20, the control amplifier 17' being provided with an additional rectifier tube corresponding to the tube 40 and connected in the same manner. With this arrangement, with the control signal between zero and the point marked A in the curves of Fig. 7, the reproducer gain is unaffected and the side speakers are off. As the control signal increases from its minimum value at A to some predetermined value indicated at B, the reproducer gain is increased as shown in the upper curve of Fig. 7, while the side speakers remain off. As the control track signal increases from B to C, the reproducer gain remains at its intermediate value and the side speakers are turned on by the second variable gain amplifier 19 in the same manner as described above in connection with Fig. 2. As the control signal increases from the arbitrary value C to the maximum value at D, the side speakers remain on and the reproducer gain is still further increased by means of the additional variable gain amplifier 80. The adjustment of the apparatus in this arrangement is accomplished in the same manner as in the preceding arrangement.

The result accomplished by the apparatus of

Fig. 8 may also be accomplished without the addition of a third amplifier by the use of the circuit shown in Fig. 9. In this circuit, the control signal is fed to the transformer 82 provided with three secondary windings to the rectifiers 83, 84 and 85. These rectifiers are provided with batteries 86, 86' and 87 connected in opposition to the control signal and having values hereinafter described. The output of the rectifier circuits is applied across the potentiometers 88, 89 and 90, and an appropriate proportion of the output voltage is filtered by the resistors 91, 92 and 93 and the capacitors 91', 92', 93' and applied to the amplifiers 94, 95 and 96. The amplifiers 94, 95 and 96 may be triodes, as shown, or they may be pentodes with their screens fed from a constant voltage source, so that moderate changes in plate voltage will not produce serious changes in plate current. The plate current for the tubes 94 and 95 is taken through the common resistor 97 which also serves as a potentiometer and is fed to these tubes through the series resistors 99 and 100, respectively. It will be apparent that any decrease in the plate current of either the tube 94 or 95, or both, will produce a corresponding decrease in the drop across the potentiometer 97 and will correspondingly affect the bias on the control grid of the amplifier tube 102. The tube 102 corresponds with the first variable gain amplifier in the preceding forms of the invention and is fed with the sound current through the transformer 101.

The tube 102 is supplied with appropriate screen and cathode potentials through the voltage divider 104 and is supplied with plate current through the resistor 103. The audio output of the tube 102 is supplied through the transformer 105 to the center speaker 106 and through the transformer 107 to the second variable gain amplifier which, in this form of the invention, is the tube 108. The tube 108 is supplied with cathode and screen potentials by the voltage divider 110 and with plate current through the resistor 109. The audio output of the tube 108 is fed to the side speakers 113 through the transformer 112.

The gain of the tube 108 is controlled by the amplifier 96, the plate current of which, applied to the potentiometer 98, controls the grid of the tube 108 through the secondary winding of the transformer 107.

It will be understood that appropriate power amplifiers are included in the circuit between the variable gain amplifiers and the loudspeakers, but these power amplifiers are not shown since they are of conventional type, as indicated in the preceding figures.

In adjusting this amplifier for the type of operation shown in Fig. 7, the voltage of the battery 87, for which of course an appropriate potentiometer supplied from an equivalent power source may be substituted, is adjusted to buck out control voltages up to the value indicated at B in Fig. 7, and the potentiometer 90 is set to drive the control tube 96 to cut-off at the control voltage indicated at C in Fig. 7. The side speakers are thus turned on as the control voltage increases from the value B to the value C in Fig. 7.

The voltage at 86' which, as indicated above, may be supplied by a battery or some other suitable power supply across a potentiometer, is set to buck out the control voltage A, which is the minimum signal from the control track and the potentiometer 89 is set to drive the control tube 95 to cut-off at the control voltage B, thereby correspondingly increasing the potential supplied

to the tube 102 through the potentiometer 97. The voltage at 86 is set to buck out the control voltage of the value indicated at C in Fig. 7, and the potentiometer 88 is set so that the control tube 94 is cut-off at the control voltage D of Fig. 7, which is the maximum voltage produced by the control track.

With no control signal, the current through the resistor 90, which is the sum of the plate currents of the tubes 94 and 95, biases the tube 102 to its minimum gain. As the tube 95 is cut off as the control voltage increases from the value A to the value B in Fig. 7, the drop across the resistor 15 is reduced, thus raising the gain of the tube 102 to an intermediate value determined by the resistor 100. An increase in the control signal from the value B to the value C of Figure 7 has no effect on the tube 102, although this increase affects the tube 108 to turn on the side speakers. As the control signal further increases from the value C to the value D, the tube 94 is cut off, correspondingly decreasing the current through the resistor 97 and increasing the gain of tube 102 from its intermediate to its maximum value. This latter increase being adjusted by the resistor 99.

I claim as my invention:

1. In combination, a sound current pickup, a sound reproduction channel, a control current pickup, a control amplifier actuated by said control current and a plurality of variable gain amplifiers in the sound reproduction channel controlled by different ranges of output level of the said control amplifier.
2. In combination, a sound current pickup, a sound reproduction channel, a control current pickup, a control amplifier actuated by said control current and a plurality of independent variable gain amplifiers in the sound reproduction channel independently controlled by different ranges of output level of the said control amplifier.
3. In combination, a sound current pickup, a plurality of sound reproduction channels, a control current pickup, a control amplifier actuated by said control current and a plurality of independent control means in the sound reproduction channels independently controlled by different ranges of output level of the said control amplifier.
4. In combination, a sound current pickup, a plurality of sound reproduction channels, a control current pickup, a control amplifier actuated by said control current and a plurality of independent variable gain amplifiers in the sound reproduction channels independently controlled by different ranges of output level of the said control amplifier.
5. In combination, a sound current pickup, a plurality of sound reproduction channels, a control current pickup, a control amplifier actuated by said control current and a plurality of control means in the sound reproduction channels controlled by the said control amplifier, at least one of said control means being a variable gain amplifier controlling the input to all of said channels.
6. In combination, a sound current pickup, a plurality of sound reproduction channels, a control current pickup, a control amplifier actuated by said control current and a plurality of independent variable gain amplifiers in the sound reproduction channels controlled by the said control amplifier, one of said variable gain amplifiers controlling the input to all of said channels.

7. In combination, a sound current pickup, a control current pickup, a main sound reproducer, auxiliary sound reproducers, a variable gain amplifier controlling the sound volume, and means controlling the operation of said auxiliary reproducers, both said variable gain amplifier and said means being controlled by different output amplitude ranges from said control current pickup.

8. In combination, a sound current pickup, a control current pickup, a main sound reproducer, auxiliary sound reproducers, a variable gain amplifier controlling the sound volume, and an additional variable gain amplifier controlling the operation of the said auxiliary reproducers, both of said variable gain amplifiers being controlled from said control current pickup, and means connected to each of said variable gain amplifiers

restricting its operation to a predetermined range of output amplitude of said control current pickup.

9. In combination, a sound current pickup, a control current pickup, a main sound reproducer, auxiliary sound reproducers, a variable gain amplifier controlling the sound volume from the main sound reproducer, and an additional variable gain amplifier independently controlling the sound volume from said auxiliary reproducers, both of said variable gain amplifiers being controlled from said control pickup, and means connected to each of said variable gain amplifiers restricting its operation to a predetermined range of output amplitude of said control current pickup.

HILLEL I. REISKIND.
